UNITED STATES PATENT OFFICE.

BURR A. KENNEDY, OF CHICAGO, ILLINOIS.

THUMB-LATCH FOR ADJUSTMENT-LEVERS.

SPECIFICATION forming part of Letters Patent No. 656,140, dated August 14, 1900.

Application filed March 23, 1900. Serial No. 9,890. (No model.)

To all whom it may concern:

Be it known that I, BURR A. KENNEDY, of Chicago, in the county of Cook and State of Illinois, have invented certain new and useful Improvements in Thumb-Latches for Adjustment-Levers, of which the following is a full description, reference being had to the accompanying drawings.

The object of this invention is to provide a cheap thumb-latch and one that can be formed to fit any thickness of lever to which it is applied.

In the drawings, Figure 1 is a plan view of the blank prior to being bent into shape for application to a lever. Fig. 2 is a side elevation of the thumb-latch as applied to a lever, a portion of the latter and catch-rod being shown in dotted lines. Fig. 3 is an end view of the parts shown by Fig. 2.

I first cut a blank from a sheet of metal, substantially of the form shown in Fig. 1, and then bend it as shown in the side view, Fig. 2, and in the end view, Fig. 3.

A is the handle end of an adjustment-lever 25 of such width and thickness as required for the purpose intended.

B is the thumb-latch, pivoted to the lever at b. The thumb-latch is provided with a catch-rod extension having an eye b', into 30 which the usual catch-rod C is hooked. The lever and rod C are broken off, as it is not necessary to show their length, as that will vary with various requirements. In order that the latch may clasp the lever, the blank

35 as cut from the sheet is given the side extensions b² and b³, each provided with a perfora-

tion for pivotal connection with a lever, as shown.

In various classes of agricultural machinery adjustment-levers of different thicknesses 40 are used, and hence one of the advantages of forming a latch in the manner described is that a single blank may be cut and by suitable bending mechanism its arms folded so as to conform to any thickness of lever. In short, 45 the blank B may be a stock article in the market and by suitable forming-dies be folded to conform to any particular lever that a manufacturer of machines using adjustment-levers may require. If metal of sufficient thickness 50 is used, the extension b³ may be dispensed with and the extension b² only serve for the purpose of connecting to the lever.

What I claim as my invention, and desire to secure by Letters Patent, is—

1. A thumb-latch blank formed of sheet metal and having extensions projecting outwardly from one end and adapted to be bent around the lever to form the pivotal supports of said latch, and being provided also with a 55 catch-rod connection.

2. A thumb-latch formed of sheet metal and having extensions projecting outwardly from one end and bent around the lever to form the pivotal supports of said latch, and a 60 catch-rod connection projecting from one of 65 said side extensions.

BURR A. KENNEDY.
